HOUSING FOR A TACHOGRAPH

George R. Stehl, Stony Brook, and Daniel November,
Kew Gardens, N.Y., assignors to Wagner Electric
Corporation

Filed June 3, 1970, Ser. No. 23,262

Term of patent 14 years

Int. Cl. D10—08

U.S. Cl. D26—14

FIG. 1

FIG. 2

FIG. 3

FIG. 4

FIG. 5

FIG. 6

FIG. 1 is a front elevation of a housing for a tachograph, showing one embodiment of our new design.

FIG. 2 is a front elevation of a housing for a tachograph, showing a second embodiment of our new design.

FIG. 3 is a side elevation of the embodiment of FIG. 2 which, without the small knob protruding in the right hand side thereof is also the side plan view of the embodiment of FIG. 1.

FIG. 4 is a rear elevation of the embodiments of both FIGS. 1 and 2.

FIG. 5 is a side elevation of a housing for a tachograph, showing a third embodiment of our new design which includes a base stand and exterior components at the rear thereof.

FIG. 6 is a front view of the embodiment of FIG. 5, showing the base stand.

We claim:

The ornamental design for a housing for a tachograph, substantially as shown and described.
